BY *Berry S. Webster* ATTORNEY

UNITED STATES PATENT OFFICE.

FRANK Z. AHL, OF SACRAMENTO, CALIFORNIA.

HOT-AIR FURNACE.

Application filed March 2, 1925, Serial No. 12,737. Renewed May 4, 1926.

This invention relates to improvements in heat furnaces of the natural draft hot air type and particularly represents an improvement over that type of furnace shown 5 in my co-pending application, Serial No. 746,550 filed October 29th, 1924.

The principal objects of the present invention are to increase the efficiency of the furnace by providing for a more thorough 10 and even distribution of the heat throughout the furnace so that a portion will not get red hot and thus cause the formation of scale; and for permitting of the free 15 out-flow of that percentage of the heat necessary to prevent condensation within the furnace, while at the same time getting all the benefits possible from the heat.

A further object is to provide a simple 20 means for reducing to a minimum the loss of heat by radiation from the outer casing or side walls of the furnace without the use of heavy and expensive insulation lagging on the outside.

A further object of the invention is to 25 construct the furnace of a number of separable parts which are very easy to assemble and dismount from each other when necessary.

These objects I accomplish by means of 30 such structure and relative arrangement of parts as will fully appear by a perusal of the following specification and claims.

In the drawings similar characters of reference indicate corresponding parts in the 35 several views;

Fig. 1 is a sectional elevation of the furnace.

Fig. 2 is a sectional plan on the line 2—2 of Fig. 1.

Fig. 3 is a perspective view of the inner 40 heat-insulating casing member.

Fig. 4 is a similar view of the base member of the main casing.

Referring now more particularly to the 45 characters of reference on the drawings, the numeral 1 denotes a cylindrical base member having a rectangular orifice 2 in one side which is surrounded by a frame 3 which has an inwardly projecting flange

4 all around the same. The base also has 50 another opening in one side covered by a screen 5. An upper casing portion 6 removably fits snugly on top of the base 1, a circumferential bead 7 on the latter limiting the downward movement of the member 6. A cap 8 similarly fits on the member 6, the cap having a desired number of air outlets 9 in the side thereof. These parts taken together constitute the outer shell of 55 the furnace and are referred to as such hereinafter.

Mounted centrally in the shell and supported as hereinafter shown is the main fire chamber 10 closed at top and bottom. In the lower end of this chamber is located 60 an upwardly facing gas or other suitable burner 11, the necessary air for which is obtained through a passage member 12 leading from the bottom of the chamber 10 to and extending over the flange 4 which 65 surrounds the intake opening 2.

Surrounding the chamber 10 and concentric therewith is a drum 13 extending to the top of said chamber but terminating short of the bottom thereof. The inner 70 periphery of this drum is spaced a suitable distance from the chamber to leave an air passage 14 opening from the shell below the chamber to the cap 8 thereabove. Air from outside the shell is admitted to 75 this passage through the screen opening 5 which is below the drum.

The outer periphery of the drum is independently corrugated from top to bottom, as shown at 15. The bottoms of these corrugations are spaced a certain distance from the inner periphery of the drum, while the outer edges thereof are similarly spaced 80 from the shell.

The drum is closed at top and bottom except for a radial passage 16 at the top thereof, which leads from the top of the chamber 10 and an outlet 17 at the bottom of the drum on the side thereof opposite to the passage 15 and also opposite to the intake 85 passage 12.

In operation the heated gases from the burner 11 pass first up through the main

chamber 10 and thence through the passage 16 to the drum 13. To get to the outlet 17 the gases must then encircle the drum while at the same time passing to the bottom thereof.

In order not to unduly hold back such flow of the gases the interior width of the drum both in vertical alinement with the passage 16 and with the outlet 17 is increased over that normally left by the corrugations and the latter are flattened out, as shown at 18 in Fig. 2.

This is a vital feature, since the entire flow of gases enters and leaves the drum through these two relative restricted openings and it is important that the flow shall not be choked adjacent these openings, as otherwise the overheating of the drum or chamber at these points is apt to occur. Further without these enlarged passages the heat cannot escape through the outlet flue in sufficient quantities to avoid condensation in the drum, which of course is an undesirable occurrence. The widened passages 18 allow the free passage of the gases around the drum from top to bottom thereof and eliminate the above named defects.

Placing the single passage 16 opposite to the outlet 17 insures that all gases must pass around the drum before leaving the same, thus giving an even heating effect and utilizing all possible heat value in the gases.

To prevent the outer surface of the drum from being overheated by the action of the hot gases as they enter the drum through the passage 16, I mount a vertical baffle plate 16^a in the drum, across the plane of the passage 16, a short distance away from the adjacent outer surface, as clearly shown in the drawings.

The fire chamber and drum are arranged as a unitary structure which is supported in the shell by transverse bars 19 mounted on the base 1 on which the bottom of the drum rests, these bars being disposed on each side of the fire chamber 10.

Depending inwardly from the base 1 adjacent the upper end thereof and extending at a downward angle is an air deflecting baffle 20 having a central opening concentric with the chamber 10 and terminating just above the radial passage 12. This causes the air entering the shell through the side opening 5 to be deflected toward the center of the furnace and causes the majority of the air to pass up close to both the inner and outer surface of the drum rather than close to the shell. The majority of the air will therefore be thoroughly heated.

To prevent any heat from the drum from being radiated to the outer shell 6 I provide an inner shell 21 open at both ends and supported by the bars 19. The shell 21 is sufficiently smaller than the shell 6 to provide an air passage therebetween, and to center

it in the shell 6 said shell 21 is provided at top and bottom with radial and outwardly projecting lips 22 formed by cutting the shell at the rim at intervals and bending the metal intermediate the cuts outwardly.

70

The shell 21 therefore takes whatever heat is radiated from the drum and this heat in turn is absorbed by the continual current of cold air passing between the shell 21 and shell 6. Asbestos or other lagging on the latter is therefore unnecessary.

The customary water pan 23 is mounted in the shell 6 and projects through the shell 21 into the space between the latter and the drum so as to provide a moistening influence on the current of air being heated.

Owing to the various parts which go to make up the furnace being detachable from each other the furnace may be easily assembled on the job and as readily dismantled when necessary.

From the foregoing description it will be readily seen that I have produced such a device as substantially fulfills the objects of the invention as set forth herein.

90

While this specification sets forth in detail the present and preferred construction of the device, still in practice such deviations from such detail may be resorted to as do not form a departure from the spirit of the invention, as defined by the appended claims.

Having thus described my invention what I claim as new and useful and desire to secure by Letters Patent is:

100

1. A hot air furnace comprising the combination of a furnace wall providing a chamber therein, a wall within the chamber providing a combustion compartment therein closed at the top and adapted to have a source of heat at its lower end, a drum surrounding the second wall in spaced relation thereto and having inner and outer walls providing a closed chamber therebetween, the outer wall being corrugated vertically, means providing an outlet passage from the bottom of the drum at one side of the combustion compartment, means providing passage communication between the combustion compartment and the drum at the top thereof at the other side of the combustion chamber, and air inlet and exit means respectively at the bottom and top of the furnace whereby air enters the furnace and is heated by passing upwardly about the drum and between the drum and combustion compartment and passes from thence outward through the said exit.

110

2. A hot air furnace comprising the combination of a furnace wall providing a chamber therein, a wall within the chamber providing a combustion compartment therein closed at the top and adapted to have a source of heat at its lower end, a drum surrounding the second wall in spaced relation

120

130

thereto and having inner and outer walls providing a closed chamber therebetween, the outer wall being corrugated vertically, a single passage between the combustion compartment and drum at the top thereof, and a single outlet passage from the drum at the bottom and at the side thereof opposite the top passage.

3. A structure as in claim 2, in which the corrugations, in the vertical plane of the passages, are decreased in depth inwardly toward the inner wall, whereby to prevent restriction of the flow of combustion gases from the top passage to the outlet passage.

In testimony whereof I affix my signature.

FRANK Z. AHL.
